UNITED STATES PATENT OFFICE.

JOHN L. FAY AND FREDRICK BIELHEN, OF ST. LOUIS, MISSOURI.

POLE-ERECTOR.

1,261,112.

Specification of Letters Patent.

Patented Apr. 2, 1918.

Application filed May 5, 1916. Serial No. 95,586.

To all whom it may concern:

Be it known that we, JOHN L. FAY and FREDRICK BIELHEN, citizens of the United States, residing at St. Louis, Missouri, have 5 invented a certain new and useful Improvement in Pole-Erectors, of which the following is a full, clear, and exact description, such as will enable others skilled in the art to which it appertains to make and use the 10 same, reference being had to the accompanying drawings, forming part of this specification.

Our invention relates to an apparatus for 15 erecting poles which carry the overhead wires and cables utilized in telegraph, telephone and electric-light service, the principal object of our invention being to provide a comparatively simple apparatus which will be effective in eliminating much 20 of the time, labor and consequent expense now involved in the erection of poles, said apparatus being mounted on a truck in order that it may be readily moved to and from the points of use and the operating parts 25 of the apparatus being adjustable upon the bed of the truck in order to facilitate the work involved in the erection of poles.

Further objects of our invention are to 30 provide an improved pole erecting device which includes a gin pole, the same being equipped with a suitable block and tackle which is utilized in lifting the poles which are to be erected to mount the gin pole and its operating mechanism upon a base and 35 to mount the latter for transverse sliding movement upon the rear portion of the bed or platform of the truck utilized for transporting the erecting device, and further to provide means preferably coöperating racks, 40 pinions and worm gearing for readily shifting the gin pole from an approximate horizontal position on the bed of the truck to a vertical position or vice versa and for raising or lowering the gin pole for a limited 45 distance after it has been swung into a vertical position. By utilizing coöperating racks, pinions and worm gearing as the means for raising and lowering the gin pole, we are able to dispense with cables, winding 50 drums, clutches and like parts usually employed for raising and lowering the gin pole.

With the foregoing and other objects in view, our invention consists in certain novel 55 features of construction and arrangement

of parts, hereinafter more fully described, claimed and illustrated in the accompanying drawings, in which—

Figure 1 is an elevational view of a truck, the same being equipped with a pole erecting device of our improved construction. 60

Fig. 2 is an enlarged side elevational view of the rear portion of the bed of the truck and showing the operating parts of the 65 erecting device.

Fig. 3 is a vertical section taken approximately on the line 3—3 of Fig. 2.

Fig. 4 is an elevational view partly in section and showing the gin pole in vertical position. 70

Fig. 5 is an elevational view looking in the direction indicated by the arrow 5 in Fig. 4, and showing the lower end of the gin pole in section.

Fig. 6 is an enlarged horizontal section 75 taken approximately on the line 6—6 of Fig. 4.

Referring by numerals to the accompanying drawings, 10 designates the bed of a truck, either horse-drawn or motor-driven 80 and fixed to the rear end of said bed and extending the entire width thereof is an angle rail 11.

Fixed on top of the bed a short distance in front of this angle rail and occupying a 85 position parallel therewith is a Z-bar 12, and fixed to the bed immediately adjacent to said angle and Z-bar are straps 13.

Arranged for sliding movement upon these straps and between the members 11 90 and 12 is a plate 14 which serves as a base for the operating mechanism of our improved device.

Fixed to plate 14 are pairs of upwardly projecting brackets 15, the upper ends of 95 which are provided with journal boxes 16 which receive the ends of a shaft 17 and mounted on this shaft between the journal box is a quadrant plate 18, the same being provided with teeth 19.

Formed integral with or fixed to this quadrant plate is a pair of rack bars 20, with the ends of which are formed integral blocks 20^a, the same having sliding connection, preferably with a rib 21, which latter 105 is formed integral with a plate 22, the latter being rigidly fixed in any suitable manner to the lower portion of a gin pole 23.

As illustrated, the blocks 20^a have dove-tailed joint connections with the rib 21, al- 110

though any other form of sliding connection may be utilized as desired.

Fixed to the bottom of the gin pole 23 is a plate 24 with which is formed integral one or more prongs 25, the same being adapted to enter the ground on which the gin pole is positioned, thereby assisting in maintaining said pole in a rigid and substantial upright position. The upper end of the gin pole is provided with a sheave 26 around which passes the cable 27 of a block and tackle (not shown). Fixed to the upper end of the gin pole are rings or eyes 28, which are adapted to receive guy ropes or the like utilized for staying the gin pole when the same is in operative position.

Positioned between rib 21 and the rack bars 20 is a member comprising a centrally arranged worm wheel 29 and a pair of pinions 20, which latter are constantly in mesh with the teeth of rack bars 20.

Formed between the worm wheel 29 and the pinions 30 are bearing portions 31 having smooth peripheries, and which latter bear directly on the face of rib 21. This arrangement is provided in order to prevent the outer ends of the teeth 30 from bearing against said rib during the time the member comprising the worm wheel and the pinions 30 is operated to raise or lower the gin pole.

Passing diametrically through the gin pole and mounted for rotation in suitable bearings fixed thereto is a shaft 32, the outer end of which is made square or non-circular in order to receive the socket of a crank handle and the inner end of said shaft carries a worm 33 which is constantly in mesh with the teeth of worm wheel 29.

A pocket 34 is formed in the face of rib 21 to accommodate the worm wheel 29, it being understood that this wheel is larger in diameter than the pinions 30. Fixed on plate 14 are boxes 35 in which are journaled trunnions 36 and formed integral with and arranged between said trunnions is a ratchet wheel 37 and a pinion 38, the latter being constantly in mesh with the teeth of quadrant plate 18.

Pivottally mounted on plate 14 is a detent 39, the hook on the end of which is adapted to engage the teeth of ratchet wheel 37. Formed through the trunnions 36, ratchet wheel 37 and pinion 38 is an opening 40, preferably square and arranged to slide freely therethrough is a square shaft 41.

When the pole erecting device is being removed to and from the point of use, the gin pole is lowered into a substantially horizontal position and overlies the body of the truck as illustrated in Fig. 1, the central portion of said pole resting on a suitable support arranged near the forward end of the truck.

When the apparatus reaches the point where a pole is to be set, the truck is driven

alongside the hole, it being understood that the pole which is to be erected has previously been positioned with its butt end adjacent to said hole.

By means of a crow-bar or like tool, the base plate 14 carrying the operating parts of the apparatus is now shifted to the side of the truck on which the work is to be done, it being understood that during this movement said base slides between parts 11, 12 and 13, and after said base has been properly positioned, shaft 41 is rotated by the application thereto of a suitable crank handle. As the shaft is thus rotated, trunnions 40 will operate in the bearings 35 and as pinion 38 is rotated, movement will be imparted to quadrant plate 18 and parts carried thereby by reason of the engagement between the teeth of pinion 38 and the teeth 19 of said plate. As a result of the movement just described, quadrant plate 18 will be partially revolved around shaft 17 with the result that gin pole 23 is swung into an upright position, as illustrated by dotted lines in Fig. 1, and after this operation has been completed, the crank handle is removed from the end of shaft 41 and applied to the outer end of shaft 32 and as this last mentioned shaft is rotated, movement will be imparted to the parts 29 and 30 by reason of the engagement of worm 33 with worm wheel 29. As a result, the gin pole is lowered until plate 24 rests upon the ground with the prong 25 positioned in the ground, and after the cables secured to rings 28 have been securely anchored, the gin pole will be held in a firm and substantial manner in its upright position.

The block and tackle associated with the gin pole is now operated in the usual manner to elevate the pole so that its lower or butt end may be dropped into the hole and thus the operation of erecting and setting the pole is easily and quickly accomplished.

Where the erecting device is moved a comparatively short distance between pole erecting operations as is the case where a line of poles are being erected, it is only necessary to elevate the gin pole a sufficient distance to free its lower end from the ground and the entire device can now be driven to the point where the next pole is to be erected with the gin pole in a vertical position or if there are overhead wires or tree branches to interfere with the movement of the apparatus as just described, the gin pole can be partially lowered or swung into an inclined position so as to escape the obstructions.

To lower the gin pole after erecting operations, it is only necessary to release the pawl 39 from the teeth of ratchet wheel 37 and impart the proper rotary movement to shaft 41 by means of a crank handle, which movement is transmitted to quadrant plate 18 and parts carried thereby, with the re-

sult that the gin pole is swung downward into a substantially horizontal position as illustrated in Fig. 1.

It will be understood that the weight of 5 the gin pole while in a vertical position and before its lower end rests upon the ground, is transmitted through worm 33, worm wheel 29 and pinions 30 to rack bars 20, from thence through shaft 17 and brackets sup- 10 porting the same to plate 14, which latter rests upon the bed of the truck, and further that this arrangement of parts particularly the worm and worm wheel practically locks the gin pole against downward movement 15 by reason of its weight, after said gin pole has been swung into a vertical position and before it has been lowered into contact with the ground. It will be noted that we employ means, preferably a pinion and toothed 20 quadrant plate, for shifting the gin pole from a horizontal to a vertical position and vice versa, and that we provide a different means which preferably includes coöperating racks, pinions and worm gearing for 25 raising or lowering the gin pole after it has been swung into a vertical position. By virtue of these mechanisms, all cables, winding drums, clutches and the like usually employed for the gin pole raising and lowering 30 means are eliminated and the raising and lowering operations can be effected quickly and with comparatively little effort on the part of the operators.

A pole erecting apparatus of our improved construction is comparatively simple, can be easily and quickly shifted into and out of operative position, can be readily moved from one side of the truck to the other, and by its use a material saving of 40 the time, labor and consequent expense now involved in the setting of wire carrying poles is effected.

It will be readily understood that minor changes in the size, form and construction 45 of the various parts of our improved pole erecting apparatus can be made and substituted for those herein shown and described, without departing from the spirit of our invention, the scope of which is set forth in 50 the appended claims.

We claim:

1. In a pole erector, a truck bed, guides transversely disposed on the rear portion thereof, a base mounted on said guides and 55 adapted to slide from one side of the truck bed to the other, a toothed segment mounted in bearings on said base, a pinion journaled in bearings on the base and engaging the teeth of said toothed segment for actuating 60 the latter, a frame carried by the segment, and a gin pole having sliding engagement with said frame.

2. In a pole erector, a truck bed, guides transversely disposed on the rear portion 65 thereof, a base mounted on said guide and

adapted to slide from one side of the truck bed to the other, a toothed segment mounted in bearings on said base, a pinion journaled in bearings on the base and engaging the teeth of said toothed segment for 70 actuating the latter, a frame carried by the segment, a gin pole having sliding engagement with said frame, and gearing mounted for operation upon the gin pole and coöperating with the frame for moving said gin pole upon said frame. 75

3. In a pole erector, a truck bed, rails arranged transversely upon the rear end portion thereof, which rails extend substantially the entire width of the truck bed, a 80 base plate mounted for sliding movement upon said rails, a member mounted on said support and adapted to rock through a vertical plane, a frame carried by said rocking member, and a gin pole mounted for sliding 85 movement upon said frame.

4. In a pole erector, a truck bed, rails arranged transversely upon the rear end portion thereof, which rails extend substantially the entire width of the truck bed, a 90 base plate mounted for sliding movement upon said rails, a member mounted on said support and adapted to rock through a vertical plane, a frame carried by said rocking member, a gin pole mounted for sliding 95 movement upon said frame, and gearing for shifting the position of said gin pole upon said frame.

5. In a pole erector, a base plate, a toothed segment mounted in bearings upon said 100 base plate so as to move through a vertical plane, means on the base plate for imparting movement to the segment, a frame carried by said segment, and a gin pole mounted for sliding movement upon said frame. 105

6. In a pole erector, a base plate, a toothed segment mounted in bearings upon said base plate so as to move through a vertical plane, means on the base plate for imparting movement to the segment, a frame carried by said segment, a gin pole mounted for sliding movement upon said frame, and coöperating means associated with said frame and gin pole whereby the latter is shifted upon said frame. 110

7. In a pole erector, a truck bed, combined guiding and retaining members arranged transversely upon the rear end portion of said truck bed, a base plate arranged for sliding movement upon the bed between 120 said guides and retaining members, and a gin pole pivotally supported upon said base plate.

8. In a pole erector, a truck bed, combined guiding and retaining members arranged 125 transversely upon the rear end portion of said truck bed, a base plate arranged for sliding movement upon the bed between said guides and retaining members, a gin pole, bearings on the base plate, and a member 130

mounted for rocking movement in said bearings, which member serves as a support for the gin pole.

9. In a pole erector, a truck bed, transversely disposed guides positioned upon the rear portion thereof, a base plate arranged for sliding movement upon said guides, bearings on said base plate, a toothed segment mounted in said bearings and adapted 10 to move through a vertical plane, means on the base plate for imparting movement to said segment, a frame carried by said segment to one side of its axis, a gin pole mounted for sliding movement upon said 15 frame, and gearing coöperating with said frame and gin pole whereby the latter is shifted upon said frame.

10. In a pole erector, a truck bed, a gin pole, a rocking frame upon which the gin 20 pole is mounted for sliding movement, bear-

ings for said frame, which bearings are disposed so that said frame moves through a vertical plane, guides transversely disposed upon the rear end portion of the truck bed, a base arranged upon said guides and adapted 25 to slide from one side of the truck bed to the other, said base serving as a support for the bearings, gearing for shifting the position of the gin pole on the frame, and separate gearing for swinging the frame 30 upon its axis.

In testimony whereof we hereunto affix our signatures in the presence of two witnesses, this 3d day of May, 1916.

JOHN L. FAY.
FREDRICK BIELHEN.
